UNITED STATES PATENT OFFICE.

WILLIAM D. FULLER, OF SPRINGFIELD, OHIO, ASSIGNOR, BY MESNE ASSIGNMENTS, TO ELLIOTT COMPANY, OF PITTSBURGH, PENNSYLVANIA, A CORPORATION OF PENNSYLVANIA.

TUBE-CLEANER.

1,189,556.

Specification of Letters Patent.

Patented July 4, 1916.

Application filed October 30, 1915. Serial No. 58,737.

To all whom it may concern:

Be it known that I, WILLIAM D. FULLER, a citizen of the United States, residing at Springfield, in the county of Clark and 5 State of Ohio, have invented certain new and useful Improvements in Tube-Cleaners, of which the following is a specification, reference being had therein to the accompanying drawings.

10 My invention relates to tube cleaners and more particularly to rotary tube cleaners.

The object of my invention is to simplify the construction by the use of fewer parts so arranged as to increase the number of sets 15 of cutters employed.

A further object is to so combine the parts that they can be easily assembled and readily taken apart for renewal or repairs.

With these and other objects in view my 20 invention consists of the constructions and combinations hereinafter described and set forth in the claims.

In the accompanying drawings which form a part of this specification Figure 1 25 is a longitudinal section of a tube cleaner embodying my invention taken on the line 1—1 of Fig. 2. Fig. 2 is a cross-section on the line 2—2 of Fig. 1. Fig. 3 is a cross-section on the line 3—3 of Fig. 1 and Fig. 30 4 is a longitudinal section on the line 4—4 of Fig. 2.

Like numerals represent the same parts in the several views.

In the drawings 1 represents a body having a front head 2 and a rear head 3, said 35 heads being formed integrally therewith to give a rigid and durable construction; and a rearward extension 4 of the body is screw-threaded as shown to attach the 40 cleaner head to a driving shaft.

The front and rear heads are provided with a plurality of pairs of oppositely disposed bores 5 and in each of these bores there is pivoted an arm 6 by a pivot pin 45 7 preferably formed integrally with said arm.

Bolts 8 having heads 9 project through openings in the free ends of each of the front arms and are screw-threaded into 50 openings in the free ends of the oppositely disposed rear arms as shown.

Rotary cutters 10 are mounted on the bolts between the arms. Said bolts project beyond the front head, the head being cut away at 11 for this purpose and rotary 55 cutters 12 are mounted thereon between said head and the heads 9 of the bolts. A spacing sleeve 13 and washer 14 are shown interposed between the cutters 12 and the front arms.

The body 1 is rectangular in cross-section and the arms 6 are provided with tail pieces 6^a which contact with the body to limit the outward swing of the arms and their inward movement is limited by contact with the 65 front head where it has been cut away at 11.

The head is assembled by first placing the arms in position on the respective heads and the bolts with the front cutters, spacing sleeve and washer thereon are then inserted 70 through the cut away portions of the front heads and the openings in the free ends of the front arms and the cutters 10 are mounted thereon as the bolts pass to the rear arms; and when the bolts are screw-threaded to the rear arms, the cutters 10 75 form the means of holding the arms in their pivoted positions in the respective heads.

It will be noted that the pivot pins are formed integrally with and project outwardly from the arms and do not extend between the arms, and by reason of this construction sufficient space is afforded to permit the use of four instead of the usual three sets of arms and cutters which greatly 80 increases the cutting capacity of the head.

Having thus described my invention I claim:—

1. In a tube cleaner, a rotary body having front and rear heads integral therewith, 90 a plurality of pairs of oppositely disposed arms, the arms of each pair being spaced apart and having pivot pins seated in openings in the respective heads and removable from the inner sides of said heads and cutters mounted between each opposing pair of arms, substantially as described.

2. In a tube cleaner, a rotary body having front and rear heads, a plurality of oppositely disposed arms having outwardly 100 extending pivot pins formed integrally therewith pivoted in and removable from

bores in the respective heads, each pair of arms being spaced apart with a bolt extending through an opening in the free end of one of said arms and secured to the other arm and cutters mounted on said bolt between said arms, substantially as described.

In testimony whereof I have hereunto

affixed my signature in the presence of two witnesses.

WILLIAM D. FULLER.
